CLAIM

The ornamental design for a couch cover, as shown and described.

DESCRIPTION

FIG. 1 is a perspective view of a couch cover showing my new design.

FIG. 2 is a front view of the couch cover shown in FIG. 1. FIG. 3 is a rear view of the couch cover shown in FIG. 1. FIG. 4 is a left side view of the couch cover shown in FIG. 1.

FIG. 5 is a top view of the couch cover shown in FIG. 1. FIG. 6 is a bottom view of the couch cover shown in FIG. 1.

FIG. 7 is an alternative perspective view of the couch cover shown in FIG. 1; and,

FIG. 8 is a top view of the couch cover shown in FIG. 1, showing the couch cover shown in FIG. 1 in an open position.

The broken lines in the drawings represent portions of the couch cover that form no part of the claimed design. The broken lines in FIGS. 7 and 8 represent environment and form no part of the claimed design. The stippling shown illustrates contour shading of the couch cover.

1 Claim, 6 Drawing Sheets
